J. E. ELGIN.

TIRE RACK.

APPLICATION FILED MAY 10, 1920.

Patented Mar. 28, 1922.

UNITED STATES PATENT OFFICE.

JOHN E. ELGIN, OF CEDAR RAPIDS, IOWA.

TIRE RACK.

1,410,740.

Specification of Letters Patent. Patented Mar. 28, 1922.

Application filed May 10, 1920. Serial No. 380,089.

To all whom it may concern:

Be it known that I, JOHN E. ELGIN, a citizen of the United States, residing at Cedar Rapids, in the county of Linn and 5 State of Iowa, have invented certain new and useful Improvements in Tire Racks; and I do hereby declare the following to be a full, clear, and exact description of the invention, such as will enable others skilled in 10 the art to which it appertains to make and use the same.

This invention relates to the storage of automobile tires and tubes in convenient form for exhibition and sale, and consists 15 in an improved rack, the parts of which, disassembled, may be compactly bundled for shipment, and at the destination may be easily installed; and when so erected be strong, durable, efficient and practically fire- 20 proof.

The invention is fully disclosed in the description and claims following, reference being had to the accompanying drawing in which:—

25 Fig. 1 is a view in perspective of my improved rack as in use. Fig. 2 is a detail view of one of the brackets on an enlarged scale.

To the floor 5 are attached standards 6 by floor-plates 7, regular gas-pipe and fittings 30 being preferably used. At the upper ends the standards are anchored in the same way by ceiling-plates 8, in which case the standards may be continuous from floor to ceiling, as will be evident, though not so illustrated. In practice the standards stop short of the ceiling, and are provided with T's 9, so that the purchaser may by adding short lengths of pipe 10 or 11, anchor to the ceiling or side wall, as may be more convenient.

40 To the standards are fitted brackets 12 having at their outer ends seats 13 for side-rails 14. For these smaller pipe is used, and is tightly clamped in position by clamp-plates 15 forming parts of the seats, the ex- 45 tended flanges of the plates and the adjacent flanges 16 of the brackets being pierced for fastening bolts 17. The rail-supporting brackets are curved upwardly as shown, both for strength and attractiveness, the trans- 50 verse flanges 16 being reinforced by depend- ing ribs 18 connecting the rail-seats with the central hubs 19. Each bracket is com- posed of a pair of identical halves, one of

which is shown at large in Fig. 2. The hub 55 has a semicircular recess of slightly less depth than the radius of the standard pipe, and is flanked each side by a flat portion 20, one of which is a continuation of the pending rib. At 21 is a shoulder, against which the end of the companion half rests 60 neatly, with faces flush all around. To give the requisite strength the lateral flange expands at the hub, as shown in Fig. 1, and indicated in Fig. 2. Through the holes 22 are inserted the clamping bolts 23. 65

To provide a shelf for inner tube boxes 24, or other merchandise, the brackets are made straight, as shown at 12^a, but are made in duplicate halves, and are clamped to the standard in the same way as the curved 70 brackets. Their straight, upper faces serve for the support of shelves 25. If metal shelves are used the entire rack is incom- bustible.

The construction admits of the brackets 75 being raised or lowered, or of their being removed, or others inserted, without disturbing any other part of the rack. As above noted, the disconnected parts may be compactly bunched, boxed, or crated for 80 shipment, and are easily and quickly assembled and erected by the use of a few bolts and screws.

Having thus described my invention, I claim:

1. In a tire-rack, in combination with supporting standards, brackets composed of similar halves, with overlapping hub portions adapted to clamp said standards, fastening bolts therefor, divided rail-seats at 90 the outer ends of the brackets, with clamp-plates therefor, fastening bolts, and rails held in said seats thereby.

2. A rail-bracket for tire-racks, comprising a pair of similar halves, with centrally divided, overlapping hubs, shouldered to match together, fastening bolts therefor, and with arms provided with terminal seats for tubular rails, co-operating clamp-plates, and fastening bolts therefor.

In testimony whereof I affix my signature in presence of two witnesses.

JOHN E. ELGIN.
